UNITED STATES PATENT OFFICE.

HARRY TOLMAN, OF MANCHESTER, NEW HAMPSHIRE.

BOOK-BACK-PRINTING MACHINE.

Application filed February 25, 1928. Serial No. 256,997.

This invention relates to devices for printing the curved backs of books. It is more particularly useful in printing or stamping gold leaf letters on such book backs.

Such stamping or lettering is now generally done by hand and requires great skill in stamping the lines of type directly across or at right angles to the plane of the book, 10 and in starting each line at such a point that it will be in the middle of the book.

In stamping gold letters, what is known as sized gold leaf is generally used and this requires that the type should be heated so 15 as to soften the wax and also the glue or other material which causes the letters to stick to the book.

The difficulty in printing book backs is that some are curved much more than others 20 and the thickness of different books varies very greatly.

I am aware that devices have been used wherein the book is held in a rocking holder, the center of oscillation of which is below 25 the book and that this is caused to move theoretically with a stamp or tool, the two rocking together.

It is obvious that if the book alone rocked, the stamp would smudge and on the other 30 hand, if the stamping tool rocked on a pivot above the book back, instead of printing clean letters, this would smudge.

I have discovered that by providing a tool holder in which there is a rack which 35 is curved convexly in an arc which conforms more or less to the arc of the book back to be printed, the center of such curved rack being below and substantially near the center of the arc of the book back and by carrying the tool on a movable pivot which 40 moves along such rack, I can use a fixed book holder and at the same time get a clean cut impression without smudging.

With my device I can quickly position a book with the center line of its back on a pre-determined center line which coincides 45 with the middle point of the line of type to be impressed thereon, and can quickly remove each book as printed and replace it by another.

By using a type holder which is pivoted to a tool holder the latter of which is pivoted to the frame of the machine, I am 50 enabled to turn the types upside down so that they can readily be removed and others reset in their place. This pivoted or hinged

action of the tool holder also allows me to bring the type down on the book back yieldingly while at the same time the line of type is always maintained at right angles to the 60 center line of the book back.

By using the curved rack and movable pivot for the type holder and particularly by interposing a compression spring, and if necessary a second pivot with suitable 65 stops, I provide mechanism which will always accurately position the line of type and permit of any desired manual pressure in rocking the line of type whereby my device is not only accurate but very sensitive. 70

In the drawings, Fig. 1 is a perspective view of a complete machine of my preferred construction showing in dotted lines a book in position.

Fig. 2 is a perspective view showing the 75 tool holder and tool with parts broken away, and a book shown in dotted lines in position.

Fig. 3 is a sectional side elevation of the type holder and tool holder showing the 80 impressing position in full lines and the type setting position in dotted lines.

Fig. 4 is an enlarged detailed view looking from the left, as shown by the direction of the arrows, on line 4—4 of Fig. 3. 85

Fig. 5 is a view as looking from the right as from the direction of the arrows, on line 5—5 of Fig. 3, of a modified construction in which the slide, slideways, spring and slide pivot are omitted. 90

In the drawings, S represents a stand shown as having four legs 1, 2, 3, 4, medially connected by cross bars 5, 6, 7, 8.

B represents a book which is held in position by book supports and clamps indicated generally by L. These include a platform 38 carried by a vertical rack 36 which can be raised and lowered by means of a pinion 35 carried by a shaft 32, at the end of which is a gear 29 operated by another gear 27, having a handle 28. The gear 27 is carried by cross piece 30 while shaft 32 is carried by a bearing 31 on cross piece 6 and bearing 33 carried by cross piece 34. A locking pawl 37 is provided to hold 27 at any 100 desired point. Platform 38 can be raised or lowered to bring the back such as 90 of a book at the desired level with reference to the stamping devices.

D is a bracket fixed to stand S and having a transverse hole 10 through which passes the right and left adjusting screw 110

24, 25, having a handle 26. This screw passes through adjoining ends of the side supports 20 and 21. Through the other ends of side supports 20 and 21 passes another right and left screw 124 and 125, such screw having a handle 126. This right and left screw 124, 125 passes through a hole in a support 9. By turning the handles 126 and 26 together the side supports are caused to move together towards and from a certain theoretical vertical plane which passes through the center line of the back 90 of the book B, and which determines the positioning of the various parts.

15 28 is an end guide carried by screw 27 which passes through support 9 and can be turned by a handle 29. This serves as an end guide for the book B so that where a number of books of the same size are to be printed in the same way the lines of printing will come in the same place.

C represents a rocker supported by arms 11, 11, which extend down on each side of bracket D. Rocker C is pivoted to bracket 25 D by means of a pivot pin 12 passed through suitable holes. I prefer to provide also a stop 112 to limit the motion of the rocker toward the book holders to a substantially horizontal position. The rocker is however 30 preferably so pivoted in the other direction that it can be turned to 90° so that it will stand in a vertical position as shown by the dotted lines in Fig. 3.

The rocker C is provided with horizontal 35 guideways 14 and 16 in which is slidable the tool carrier F. 15 is a thumb screw which passes through carrier F and engages rocker C so that the tool carrier can be held in any desired position.

40 The end of tool carrier F which is nearest the book holders is bent at right angles and cut away so as to form the slideways 60, 60, and the bottom bar 61 in which preferably is a spring pin 62 to hold in place 45 the bottom end of spring 40 the upper end of which is seated in counterbore 162 and engages and holds resiliently up in place the slide 58 slidable in slideways 60, 60.

H is a gear casing pivoted to slide 58 by 50 means of a bolt or pivot 59 so that it can rock in a vertical plane.

Gear casing H is preferably convex at the top and has at the top a slot 53 and at the bottom a slot 54 of a size to receive the head 55 157 of stud E which can move in these slots with a smooth running fit. Its axle shank 57 extends out from casing H through stud slot 55.

At the bottom of gear casing H is a rack 60 R which is convex with reference to the position of the book B. Y is a coil box provided on the inside with heating elements U connected by means of wires W with a source of electric energy by means of which it can 65 be heated at will.

This coil box Y is shown as fixed to the axle shank 57 of stud E and revoluble on this axle 57 shank in engagement with rack R is the gear G. It will be seen that coil box Y can therefore rock transversely of book 70 B on stud E and can also move in an arc transversely as the gear G moves on rack R.

There is also in this construction a double pivotal action, because pivot 59 permits the gear casing H to rock at the same time that 75 coil box Y rocks on stud E. Preferably I provide stops 52, 52 on gear casing H which limits its movement by striking the side of slideways 60, 60, and I also provide stops 152, 152 on coil box Y which limits its rocking movement by striking gear casing H. The type holder A, known to the printing trade as a pallet is of well known form and is provided with slidable type holding jaws J, J, between which the movable type members T, T can be set, the jaws J, J, being adjustable by the right and left thumb screw 70, 70. By this mechanism the center line of the type is always at the same point, which is preferably the center line of the 80 handle K.

This type holder A is hinged or pivoted by means of the hinged members 47, 48 and 45, 46 to the coil box Y in such manner that it can be swung over an arc of more than 90°. 95 As shown in the dotted lines in Fig. 3, it and the tool holder can be swung up to the vertical position which makes it very easy to change or reset the type.

44 is a spring on rod 49 which tends to 100 hold type holder A against the coil box Y.

In Fig. 5, I show a tool holder 80 which is similar to F but is bent down at right angles at its end 81 and to this the gear casing H is fixed by two screws 82, 83 so that it has no 105 pivotal movement as does the other construction on pivot 59. The curve of the rack such as 85 may preferably be somewhat more than that of the ordinary book and the book preferably is adjusted in a position where its back will allow the type holder and type to come down on it firmly without being held back by the stop 112.

My machine may be used with ink instead of gold leaf and pictures or cuts may be used 115 in place of type.

I claim:

1. In a book back printing machine, the combination with a stand; of a book holder carried by the stand including an adjustable bottom book support, an adjustable end guide and a side clamp having means to move its jaws equally and simultaneously towards and from a bracket fixed to the stand centrally between the jaws; said bracket; a 120 rocker slide carried on a horizontal pivot by said bracket; a tool carrier adjustable and slidable in the rocker slide in a direction parallel to and midway between said jaws; guideways extending down at right angles 125 130

from the end of the tool carrier; a gear casing resiliently slidable in said guideways said gear casing including a convexly curved gear rack, curved stud head guides and a 5 curved stud slot; a tool pivot stud including a head in engagement with said curved head guides and an axle shank; a gear in engagement with the gear rack and revoluble on said axle shank; an electrically heated coil 10 box fixedly carried by said axle shank; a type holder horizontally and transversely hinged to the coil box and having means to receive and hold type in place; and an operating handle fixed to the type holder.

15 2. In a book back printing machine, the combination with a stand; of a book holder carried by the stand including an adjustable bottom book support, an adjustable end guide and a side clamp having means to move its 20 jaws equally and simultaneously towards and from a bracket fixed to the stand centrally between the jaws; said bracket; a rocker slide carried on a horizontal pivot by said bracket; a tool carrier adjustable and slid- 25 able in the rocker slide in a direction parallel to and midway between said jaws; a gear cas- 30 ing transversely fixed to the end of said tool carrier and including a convexly curved gear rack, curved stud head guides and a curved 35 stud slot; a tool pivot stud including a head in engagement with said curved head guides and an axle shank; a gear in engagement with the gear rack and revoluble on said axle shank; an electrically heated coil box fixedly 40 carried by said axle shank; a type holder horizontally and transversely hinged to the coil box and having means to receive and hold type in place; and an operating handle fixed to the type holder.

45 3. In a book back gold leaf lettering ma- 50 chine, the combination with a stand having means to hold a book; with a tool carrier so pivoted to the stand as to swing on a pivot which is perpendicular to a plane passing 55 through the middle of the book and its back; a gear casing transversely fixed to the end of said tool carrier and including a convexly curved gear rack, curved stud head guides and a curved stud slot; a tool pivot stud including a head in engagement with said curved head guides and an axle shank; a gear in engagement with the gear rack and revoluble on said axle shank; an electrically heated coil box fixedly carried by said axle shank; a type holder horizontally and transversely hinged to the coil box and having means to receive and hold type in place; and an operating handle fixed to the type holder.

60 through the middle of the book and its back; a gear casing transversely fixed to the end of said tool carrier and including a convexly curved gear rack, curved stud head guides and a curved stud slot; a tool pivot stud including a head in engagement with said curved head guides and an axle shank; a gear in engagement with the gear rack and revoluble on said axle shank; an electrically heated coil box fixedly carried by said axle shank; a type holder horizontally and transversely hinged to the coil box and having means to receive and hold type in place; and an operating handle fixed to the type holder.

65 4. In a book back gold leaf lettering ma- 70 chine, the combination with a stand having means to hold a book; with a tool carrier so pivoted to the stand as to swing on a pivot which is perpendicular to a plane passing through the middle of the book and its back; a gear casing transversely fixed to the end of said tool carrier and including a convexly curved gear rack, curved stud head guides and a curved stud slot; a tool pivot stud including a head in engagement with said curved head guides and an axle shank; a gear in engagement with the gear rack and revoluble on said axle shank; and type holding means carried by said axle shank.

75 5. In a book back printing machine, the combination with a stand having means to hold a book; with a tool carrier so pivoted to the stand as to swing on a pivot which is perpendicular to a plane passing through the middle of the book and its back; a gear casing transversely fixed to the end of said tool carrier and including a convexly curved gear rack; an axle shank; a gear in engagement with the gear rack and revoluble on said axle shank; printing means carried by 80 the axle shank; and means to hold the printing means and the gear casing together.

HARRY TOLMAN.
